(57) **CLAIM**

The ornamental design for an all-terrain vehicle body, as shown and described.

DESCRIPTION

FIG. 1 is a top, front and left side perspective view of an all-terrain vehicle body showing our new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken lines in the figures show portions of the all-terrain vehicle body that form no part of the claimed design.

1 Claim, 6 Drawing Sheets
